UNITED STATES PATENT OFFICE.

CECIL MILTON HEPWORTH, OF LONDON, ENGLAND.

APPARATUS FOR USE IN SYNCHRONOUSLY OPERATING COMBINED KINEMATOGRAPHS AND SOUND-PRODUCTION APPARATUS.

1,023,846.

Specification of Letters Patent.

Patented Apr. 23, 1912.

Application filed June 23, 1909. Serial No. 503,902.

To all whom it may concern:

Be it known that I, CECIL MILTON HEPWORTH, subject of the King of England, residing at 17 Cecil Court, Charing Cross, London, England, have invented a certain new and useful Apparatus for Use in Synchronously Operating Combined Kinematographs and Sound-Production Apparatus, of which the following is a specification.

10 This invention relates to apparatus for use in synchronously operating combined kinematographs and sound production apparatus such as gramophones or the like.

According to this invention apparatus for 15 the purpose described consists of two members arranged to receive reciprocating motion from the kinematographs and sound production apparatus respectively and thereby engage and operate an intermediate 20 member in such a way that the latter is not moved in a linear direction when the movements of the kinematograph and sound production mechanism are synchronous, but does receive such motion when the movements are asynchronous.

The invention will best be understood by 25 the following description taken in conjunction with the accompanying drawings which illustrate one method of carrying this invention into effect and in which:—

Figure 1 is an elevation showing the front of the apparatus. Fig. 2 is a plan view of the same, Fig. 3 is an elevation showing the back of the apparatus with a portion of the 35 lamp bulb broken away to show the transparent portion behind the pointer, Fig. 4 shows in plan part of a gramophone disk with a special starting arrangement, Fig. 5 is an elevation of one form of contact making device as attached to the gramophone, Fig. 6 is a plan view of the same, Fig. 7 is a view showing one form of contact making device attached to the kinematograph, Fig. 8 is a diagram showing the electrical connections between the different parts of the 40 apparatus. Fig. 9 is a detail section on the line 9—9 of Fig. 5.

Referring to Figs. 1 and 3 mounted on a base A is a frame work comprising two upright posts A' and A² joined together by four horizontal bars A³. The spindle B' of a ratchet wheel B is adapted to slide between the two upper and two lower of the bars A³ respectively, and it can also rotate.

To the post A' a lug A⁴ is attached and an 55 armature C is pivoted on a pin C' in this lug. Attached to a pin C⁴ at the opposite end of the armature C a pawl D is pivoted and this pawl engages the ratchet wheel B. A continuation of the pawl D around its 60 pivot is formed into a hook D' to which a spring E is attached. A second pawl F engages the same side of the ratchet wheel as the pawl D, the pawl F being pivoted at F' to a lug on the post A². This second 65 pawl prevents a backward movement of the ratchet wheel B due to the friction of the pawl D. A continuation of the pawl F around its pivot is formed into a hook F' to which the opposite end of the spring E 70 is attached as shown. An electro-magnet G is fixed to the base A so as to operate the armature C. A lug A⁵ is fixed to the base A and to a point H' thereon an armature H is pivoted. At the opposite end of the 75 armature H' a pawl I is pivoted and this pawl engages the ratchet wheel B. A continuation of the pawl I around its pivot is formed into a hook I' to which a spring J is attached. A second pawl K engages the 80 same side of the ratchet wheel B as the pawl I, the pawl K being pivoted to the lug A⁴ on the post A'. This pawl also prevents a backward movement of the ratchet wheel due to the friction of the pawl I. A continuation of the pawl K around its pivot 85 is formed into a hook K', to which the opposite end of the spring J is attached. A second electro-magnet L attached to the base A operates the armature H. A pointer M 90 is pivoted to a link M³ which in turn is pivoted to the post A'. This pointer is engaged by the spindle B' of the ratchet wheel B so that any longitudinal movement of the ratchet wheel spindle will cause the pointer 95 to be moved to the left or right as the case may be. A transparent disk is attached to this pointer, one half M' of this disk being of one color and the other half M² of another color. An electric lamp M⁴ is arranged behind the pointer, the bulb of this lamp being covered with an opaque substance except for a small circle which is hidden by the pointer when the latter is in its middle position as indicated at m⁴ in 100 Fig. 3. When the pointer is displaced to one side or the other, one half M' or M² of the transparent screen is illuminated and

consequently a light of one or the other color shown.

In Fig. 4 is illustrated the means preferably employed for assuring correct starting of the gramophone record. The gramophone needle is placed in the slot R' and the record moved around in the direction of the arrow until the needle is opposite the mark R when the record is in the correct position for starting.

The actual contact makers employed in practice are illustrated in Figs. 5 to 7. Referring to Fig. 5 a bracket P is constructed so that one end P' can rest on the gramophone case. The other end is provided with a spindle rotatably mounted therein to which is attached a toothed wheel P² engaging with a second toothed wheel P³. The ratio of the number of teeth in the toothed wheels is such that when the gramophone and kinematograph are operated synchronously each of the electro-magnets is energized the same number of times per second. It is obvious that instead of employing only two toothed wheels more than two may be employed. The spindle P⁴ rests on the disk pin of the gramophone and has a small projecting ridge P⁵ at its end. This ridge enters a slot in the disk pin P⁶. By this means the spindle is rotated as the disk pin rotates. Fixed to the second toothed wheel P³ is a contact maker N and one or more springs N' are made to press against it. This contact maker consists of a disk of insulating material N² with metallic contacts N³ in the form of segments secured therein, opposite contacts being connected in any convenient manner. A circuit is established between the battery and the electro-magnet G when the springs N' press against two opposed contacts on the contact maker. In this manner the speed of operation of the gramophone controls the number of times per second that the electro-magnet G is energized. The bracket P is made so that it can be lifted right off the gramophone case in order that the gramophone records may be changed.

An improved advantage of the electric contact making mechanism just described is that it may be easily fitted to existing gramophones.

In Fig. 7 is illustrated one form of contact maker O as applied to a kinematograph. It is of the same type as the contact maker N and is fixed to the spindle that is rotated by the handle which operates the kinematograph. Bearing on each side are two springs O' mounted on blocks O² of insulating material and having terminals O³ for the necessary electrical connections. Contact is made in a similar manner to that described in connection with the gramophone contact maker and as the handle of

the kinematograph is rotated it controls the number of times per second that the electro-magnet is energized.

Fig. 8 is a diagrammatic illustration of the apparatus and its connections, arranged according to this method of carrying this invention into effect, and the method of operation will be described in conjunction therewith. As the contact makers N and O rotate their respective electro-magnets G and L become energized whenever connection is made with the battery through their respective contact makers, and this takes place with the form of contact maker illustrated, four times in every revolution. As the armature C of the electro-magnet G for example, is attracted, the pawl D attached thereto passes over a tooth on the ratchet wheel B. When the armature C is released owing to the action of the spring E the ratchet wheel is rotated through a distance corresponding to one tooth. The same operation takes place with the armature H of electro-magnet L when the latter is energized. If the speeds of the contact makers N and O are alike, the armatures operated by their respective electro-magnets will rotate the ratchet wheel B but will not move it longitudinally. However, if the kinematograph is being operated at too high a speed its contact maker will make a higher number of revolutions and consequently make electrical connection more frequently than the corresponding contact maker on the gramophone. The result of this will be that the armature H will move its pawl I more frequently than the armature C moves its pawl D, and the ratchet wheel receiving a greater number of thrusts at one side than it does at the other will be moved in a longitudinal direction. When this takes place the pointer M attached to the spindle of the ratchet wheel will move so that one or the other half, M' or M², of the transparent screen will appear in front of the illuminated circle on the electric lamp, thereby indicating to the operator, according to whichever color is assigned to the kinematograph, that such kinematograph is being worked too quickly. If the operator then lowers the speed of operation of the kinematograph and allows the gramophone to increase its speed slightly, the ratchet wheel will be moved back to its proper position owing to the action of the pawl D moving the ratchet wheel B against the pawl K.

The apparatus herein described serves to give an indication, as explained above, as to whether the kinematograph and gramophone are operating synchronously, and if they are not, the movements of the kinematograph may be controlled manually so as to bring the movements of the two in synchronism. The longitudinal movement of the ratchet wheel may, however, be utilized

so as to keep the kinematograph and gramophone in synchronous operation. That is to say, the movement of the movable member may be utilized in any manner known to those skilled in the art to synchronize the speeds of the two machines.

Obviously it is not intended to restrict the use of a commutator to that type of kinematograph which is operated by a handle, as a commutator can quite easily be fitted to an electric motor used to operate the kinematograph.

Preferably the indicating or controlling device described above is employed in combination with the contact-making mechanism just described, but it is within this invention to employ either independently.

It is obvious that various modifications may be made in the methods of carrying this invention into effect, those described above being merely by way of example.

What I claim as my invention and desire to secure by Letters Patent is:—

1. The combination of a kinematograph and a device reciprocated in synchronism therewith, a sound-producing apparatus, and a second device reciprocated in synchronism therewith, and a rotatably mounted member having a shifting axis engaged by said reciprocating devices to cause the member to rotate about its axis when the kinematograph and sound-producing apparatus are in synchronism with each other and to cause the axis of said member to move in a lineal direction when they are not in synchronism with each other, substantially as described.

2. The combination of a kinematograph and a pawl reciprocated in synchronism therewith, a sound-producing apparatus and another pawl reciprocated in synchronism therewith, a ratchet wheel operated by said pawls and bearings adapted for the rotation and linear displacement of said wheel, substantially as described.

3. The combination of a kinematograph, an electro-magnet and a pawl carried by the armature of said electro-magnet, a sound-producing apparatus, a second electro-magnet and another pawl carried by the armature of said second electro-magnet, means for energizing the respective electro-magnets in synchronism with the motions of the kinematograph and sound-producing apparatus, a ratchet wheel operated by said pawls and stationary bearings adapted for the rotation and displacement of said wheel in a direction transversely of its axis, substantially as described.

4. The combination of a kinematograph, an electro-magnet and a pawl carried by the armature of said electro-magnet, a sound-producing apparatus, a second electro-magnet and another pawl carried by the armature of said second electro-magnet, means for energizing the respective electro-magnets in synchronism with the motions of the kinematograph and sound-producing apparatus, a ratchet wheel operated by said pawls, stationary bearings adapted for the rotation and displacement of said wheel in a direction transversely of its axis, a frame arranged to rest on the top of the sound-producing apparatus, a spindle mounted in said frame, said spindle having a projection adapted to engage a hole in the top of the spindle of the sound-producing apparatus, a gear wheel mounted on said spindle and gearing with a contact device for controlling the energization of the second electro-magnet.

nets in synchronism with the motions of the kinematograph and sound-producing apparatus, a ratchet wheel operated by said pawls, stationary bearings adapted for the rotation and displacement of said wheel in a direction transversely of its axis and a pointer moved by said ratchet wheel, substantially as described.

5. The combination of a kinematograph, an electro-magnet and a pawl carried by the armature of said electro-magnet, a sound-producing apparatus, a second electro-magnet and another pawl carried by the armature of said second electro-magnet, means for energizing the respective electro-magnets in synchronism with the motions of the kinematograph and sound-producing apparatus, a ratchet wheel operated by said pawls, stationary bearings adapted for the rotation and displacement of said wheel in a direction transversely of its axis, a pointer moved by said ratchet wheel, transparent vanes on said pointer, and a source of illumination whereby one or other of said vanes is illuminated according to the direction of linear movement of said ratchet wheel, substantially as described.

6. The combination of a kinematograph, an electro-magnet and a pawl carried by the armature of said electro-magnet, a sound-producing apparatus, a second electro-magnet and another pawl carried by the armature of said second electro-magnet, means for energizing the respective electro-magnets in synchronism with the motions of the kinematograph and sound-producing apparatus, a ratchet wheel operated by said pawls, stationary bearings adapted for the rotation and displacement of said wheel in a direction transversely of its axis, a frame arranged to rest on the top of the sound-producing apparatus, a spindle mounted in said frame, said spindle having a projection adapted to engage a hole in the top of the spindle of the sound-producing apparatus, a gear wheel mounted on said spindle and gearing with a contact device for controlling the energization of the second electro-magnet.

7. The combination of a kinematograph, an electro-magnet and a pawl carried by the armature of said electro-magnet, a sound-producing apparatus, a second electro-magnet and another pawl carried by the armature of said second electro-magnet, means for energizing the respective electro-magnets in synchronism with the motions of the kinematograph and sound-producing apparatus, a ratchet wheel operated by said pawls, stationary bearings adapted for the rotation and displacement of said wheel in a direction transversely of its axis, a frame arranged to rest on the top of the sound-producing apparatus, a spindle mounted in said frame, said spindle having a projection

adapted to engage a hole in the top of the spindle of the sound-producing apparatus, a gear wheel mounted on said spindle and gearing with a contact device for controlling the energization of the second electro-magnet, a rotatable make and break contact-making device mounted on the operating handle of the kinematograph and spring pressed contact blades adapted to press on said contact-making device whereby the first electro-magnet is energized at times dependent on the rate of movement of the kinematograph mechanism.

8. The combination of a kinematograph and means associated therewith for producing reciprocating motion, a sound-producing apparatus and means associated therewith for producing reciprocating motion, a slideable and rotatable member, means operated by the combined action of the aforesaid means for rotating said member when the movements of the kinematograph and sound-producing apparatus are synchronous, and for sliding the member when said movements are asynchronous, substantially as described.

9. A regulating device for a combined kinematograph and sound-producing appa-

ratus, comprising a member mounted for rotation and lineal movement, means actuated by the kinematograph for rotating said member, and means actuated by the sound-producing apparatus for rotating said member in the same direction, said means acting on opposite sides of said member and each tending to rotate it about the point of application of the other means as an axis; substantially as described.

10. A regulating device for a combined kinematograph and sound-producing apparatus, comprising a member mounted for rotation and lineal movement, means actuated by the kinematograph and sound-producing apparatus for causing rotation of said member when they are in synchronism and for causing a lineal and rotating movement of said member when they are not in synchronism, substantially as described.

In testimony whereof I have signed my name to this specification in the presence of two subscribing witnesses.

CECIL MILTON HEPWORTH.
